United States Patent Office.

MILES MAYALL, OF ROXBURY, MASSACHUSETTS.

Letters Patent No. 73,909, dated January 28, 1868.

IMPROVEMENT IN MACHINE FOR OILING WOOL.

The Schedule referred to in these Letters Patent and making part of the same.

TO ALL PERSONS TO WHOM THESE PRESENTS SHALL COME:

Be it known that I, MILES MAYALL, of Roxbury, in the county of Norfolk, and State of Massachusetts, have invented certain new and useful Improvements in Wool-Oiling Machines; and that the following description, taken in connection with the accompanying plate of drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

The object of the present invention is to form a self-regulating apparatus that will not only insure a perfect and uniform distribution of oil upon wool, but press it into the same, so that the wool becomes thoroughly saturated therby, and can be used immediately.

By thus preparing the wool for instant use, an inferior quality of oil, or composition of oil and other materials, can be used to better advantage than has heretofore been possible, as there is no time for the oil to become gummy, or particles of the composition to evaporate, as has been the case where the wool was spread out, and obliged to remain some time after being sprinkled, or otherwise prepared with oil. Moreover, the wool can be more easily and better carded and spun when thus freshly oiled.

The improvements heretofore made in wool-oiling machines have proved objectionable on many accounts, principal among which are the disadvantages arising from their complicated construction, the numerous parts occupying too much room, and interfering with the operative; the constant attendance required in operating them; the imperfect manner in which the oil is distributed over the wool, one portion of the wool receiving a large quantity of oil, and another little or none; and from various other causes that need not be stated further herein.

The most essential advantages of my improved wool-oiling apparatus are the time, labor, and expense saved by its self-regulating action; the simplicity of its construction and operation, requiring no pulleys, gearing, or complicated connection with the carding-machine; regulating the flow and the equal distribution and pressure of the oil on the wool; the cleanliness with which the oil is kept, and the prevention of its congealation; the immediate use of the wool after being freshly oiled, and the better working of the same in consequence thereof.

Having thus stated some of the many advantages of my improvements, I will now proceed to describe in detail the arrangement of the same. My improved apparatus for oiling wool is represented in the accompanying plate of drawings, of which—

Figure 1 is a top view or plan,

Figure 2 a central vertical longitudinal section, and

Figure 3 a central vertical transverse section.

a a a, in the drawings, represent the frame of a wool-feeding machine, with which is connected a feeding-apron, *b b*. Attached to one end of the frame *a a* are standards *c c*. Fitted over the standards *c c*, so as to be raised or lowered theron, are tubes *d d*, attached to the bottoms of sockets *e e*, through which are made to revolve hollow plug-shafts *f f*, attached to wheels *g g*. In the top of the circumference of the plug-shafts *f f*, in the center of the sockets *e e*, apertures *h h* are formed to serve as cocks, so that by turning the shafts *f f*, the oil or composition used is admitted to or excluded from them, according to the direction in which they are turned. Screwed into or otherwise connected with the ends of the plug-shafts *f f*, opposite to those to which the wheels *g g* are attached, is a hollow shaft, *i i*, having a slot or a series of apertures, *k k k*, &c., so formed in its circumference as to be at such an angle with the cocks *h h*, when they are opened, as to allow the oil to drip from the said apertures *k k*, and not to steadily flow from them. Connected with the shaft *i i* by bearings *l l*, and made to turn with or independently of the shaft *i i*, is a perforated or gauze cylinder, *m m*. Above the sockets *e e*, and connected with them, are other sockets, *n n*. In the sockets *n n* work stop-cocks *o o*, operated by thumb-screws *p p*, which also operate indicators *q q* attached to the opposite ends of the stop-cocks *o o*, and which revolve in front of dial-plates *r r* placed on the face of the sockets *n n*. Connected with the tops of the sockets *n n* are tubes *s s*, which connect with the bottoms of reservoirs *t t*. Apertures *u u* are formed in the tops of the reservoirs *t t* for the admission of oil, &c., and are closed by means of screw-caps *v v*.

The operation of my improved apparatus is as follows: The reservoirs *t t* being filled with oil, or other material used in preparing wool, the oil, &c., is forced by the pressure of its own weight through the tubes *s s*, the flow therein being regulated by the stop-cocks *o o*, so that a large or small quantity of oil can be admitted through the cocks *o o* into the sockets *e e*. By turning the thumb-screws *p p*, attached to the cocks *o o*, the position in

which the cocks *o o* should be turned to admit of the desired amount of oil is plainly shown by the indicators *q q* on the dial-plates *r r*. The plug-shafts *ff* being turned in proper position by means of the wheels *g g*, which are connected with the main belt of the carding-machine by any suitable mechanical devices, automatical or otherwise, the oil flows from the tubes *s s*, through the apertures or cocks *h h*, into the hollow shaft *i i*, from which it is distributed through the slot or apertures *k k k*, formed in the circumference thereof, upon the inside of the perforated or gauze cylinder *m m*, which is made to revolve around the shaft *i i* by the wool *w w* pressing against it as it is fed along by the feeding-apron *b b*. The distributing-shaft *i i* is so arranged in regard to the cocks *h h* that, when the cocks *h h* are opened, the apertures *k k k* are placed at such an angle as to produce a regular and constant dripping of the oil upon the cylinder *m m*, and not to allow its flowing in a steady stream, which would be the case if the shaft *i i* were so operated as to bring its apertures *k k k* directly on the under side thereof. The flow of the oil into the shaft *i i* is regulated, or entirely shut off therefrom, according to the extent to which the shafts *ff* are turned.

By the means above described, the cylinder *m m*, as it revolves round the shaft *i i*, becomes evenly and suitably supplied with oil, no one part of its circumference receiving any more or less oil than another, and as it passes slowly over the wool *w w*, it distributes and presses an equal quantity of oil upon all parts alike, and, by means of the cocks *h h*, the quantity of oil applied can be varied at pleasure. The tubes *d d* are arranged to rise and fall on the standards *c c*, to obviate any obstruction that the cylinder *m m* may meet with, so that in case a larger quantity of wool than could otherwise pass between it and the feed-apron should collect, the cylinder *m m*, instead of being checked thereby, is lifted over the same without interfering with its operation.

Fastened to a bar, *x x*, attached to the tubes *s s*, and extending lengthwise over the top of the cylinder *m m*, is a wire or other brush, *y y*, and inside of the cylinder *m m*, extending the length thereof, is a similar brush, *z z*, attached to the shaft *i i* by standards *a a*, or by any other suitable means. These brushes *y y* and *z z* remain stationary, and, as the cylinder *m m* revolves, they are brought to press against and through its meshes or perforations in such a manner as to prevent any possibility of the meshes or perforations becoming clogged with oil, or otherwise obstructed.

From the foregoing description it will be seen that the desired flow of the oil being regulated by the adjustment of the cocks *o o* to the proper position designated by the indicators *q q* upon the dial-plates *r r*, and the apertures *k k k* of the shaft *i i* arranged at the proper angle, no further care or attention is necessary for operating the apparatus, as the cylinder *m m* is constantly and uniformly supplied with oil from the reservoirs *t t* by the pressure exerted by the weight of the oil, and is operated by the wool *w w* pressing against it as it is fed along by the feed-apron *b b*. It will also be observed that the oil being deposited in covered reservoirs, it is thereby protected from all dust and dirt likely to arise, and, in consequence of which, the oil always flows freely, and all clogging and obstruction of the passages through which it passes are prevented. Moreover, the oil being thus kept in a heated room, all liability of its congealing, and the disadvantages arising therefrom, are obviated.

By my improved apparatus, the wool is freshly as well as thoroughly oiled, and ready for instant use, thereby causing it to card and spin better, particularly in the case where an inferior quality of oil is used, as the oil, after lying some time, is apt to become gummy, and interfere with the working of the wool; besides, composition of oil and other materials can be used to a greater advantage where the wool is immediately used after oiling, as no chance is given for the particles of the composition to evaporate, as they are liable to do when left standing any length of time, as was necessary in the method heretofore used of spreading the wool upon a floor, and sprinkling it with oil or composition. Moreover, a great economy in the consumption of oil or other material used is effected, and the danger of fire, often occasioned by the floor becoming impregnated with oil, is prevented.

Having thus described my improvements, I shall state my claims as follows:

What I claim as my invention, and desire to have secured to me by Letters Patent, is—

1. The combination of the elevated reservoir, connecting-tube, and hollow perforated shaft, substantially as and for the purpose set forth.
2. The combination of the elevated reservoir, the connecting-tube, hollow perforated shaft, and revolving perforated cylinder, from which the oil is applied to the wool, substantially as described.
3. In combination with the tube for supplying the oil from the reservoir, an oscillating perforated hollow shaft, *i*, from which the oil will be made to flow, on starting the carding-machine, and be cut off on stopping the same, by means of connecting-mechanism acting upon the arm or wheels *g*, substantially as described.
4. Regulating and indicating the supply of oil to the cylinder *m* by means of the valves *o o* and *h h*, indicator *q q*, and dial-plate *r r*, substantially as set forth.
5. In combination with a perforated cylinder *m*, the brushes *y* and *z* for cleansing the apertures, arranged substantially as set forth.
6. The combination of the endless apron, and cylinder *m*, when the frame supporting the latter is constructed with pipes *d d*, resting upon standards *c* to permit the cylinder to rise and fall, substantially as set forth.
7. The combination and arrangement of the perforated cylinder and perforated shaft *i*, as and for the purpose set forth.

MILES MAYALL.
